UNITED STATES PATENT OFFICE.

AUSTIN L. WERTZ, OF LAKEWOOD, OHIO, ASSIGNEE OF ONE-HALF TO MORTIMER C. ROSENFIELD, OF CLEVELAND, OHIO.

FROSTPROOF DRAIN VALVE.

Application filed December 28, 1925. Serial No. 77,967.

This invention relates to a drain valve that is especially adapted for use with large outdoor storage tanks for containing oils and other liquids.

5 It is a well known fact that during the fall and early winter, when the temperature drops considerably below that prevailing during the preceding summer months, there is quite an accumulation of water of condensation in the bottoms of tanks of the 10 above mentioned class, and, later, as the temperature drops below freezing, the water about the walls of the tanks and within the valves freezes and causes considerable difficulty in draining or drawing off the oil from the tanks, torches usually having to be resorted to to thaw out the valves before the tanks can be drained or the oil drawn off. This is not only a time consuming and 15 troublesome operation, but the use of the torch in such close proximity to the combustible contents of the tanks is hazardous.

The primary purpose of my invention is to provide a so-called frost-proof drain 25 valve for tanks of the class above referred to which is immune from freezing so that, at any time, the tank may be drained by the simple operation of the valve.

Other objects are to provide a comparatively simple and substantial construction 30 that is durable and highly efficient; that is convenient of manipulation; and that incorporates a locking shroud which, when in protecting position, encloses the stuffing gland 35 and the valve stem and protects them from being tampered with, said shroud being designed for use as a means for operating the valve when it is removed and its position reversed.

40 The foregoing objects are attained in the embodiment of the invention illustrated in the accompanying drawing wherein Fig. 1 shows a longitudinal sectional view through the valve and the adjacent portion of a tank to which the valve is applied; and Fig. 45 2 is a front end view of the valve.

The valve is comprised of a relatively long hollow casing 1 which terminates at one end in a valve seat 2 and at the other is 50 formed with a boss 3 having a bore that is in axial alignment with the valve seat 2. The inner end of said bore is provided with a square thread for cooperation with a corresponding thread on a valve stem 5 which 55 carries, as its inner end, a valve disk or body

6 that is designed to engage the seat 2 when the stem is rotated in a direction to feed it forwardly through the medium of its before-mentioned thread. Outwardly beyond the square threads wherewith the threads of the valve stem 5, inwardly of its threaded portion, is strengthened by longitudinal ribs 9 that merge with the valve disk or body 6, it is cylindrical forwardly of said threads and, at its extreme outer end is reduced in diameter, a part adjacent said reduced end being squared or otherwise formed, as shown at 10, for the reception of a wrench or other valve operating tool. To prevent the stem from being fed inwardly too far, a stop pin 12 is passed through the stem immediately 75 inwardly of the wrench receiving portion 10 for engagement with the nut 8 of the stuffing gland.

Designed to fit over the outwardly extending portion of the boss 3 is a locking shroud 15 which has a laterally extending perforated ear 16 that may be arranged in proximity to a similar ear 17 projecting forwardly from the internally threaded outlet extension 18 of the casing 1. The shroud 15 may be secured against withdrawal from the boss 3 by a pad lock 19 whose bow is adapted to be engaged through the perforations of the ears 16 and 17. The reduced outer end of the shroud 15 has a socket 20 of a size and shape to fit upon the wrench receiving portion 10 of the valve stem. When it is desired to operate the valve the lock 19 is removed, the shroud is withdrawn and reversed and its socket 20 is engaged over the 95 portion 10 of the stem. When in this position, the shroud may be effectively employed as a wrench for operating the valve.

The casing 1 is provided with an external thread 25 that is spaced a material distance 100 outwardly from the region of the valve 6. This thread provides means by which the valve may be attached to a tank wall. In Fig. 1, the thread 25 is shown as screwed into a flange 26 on the outer side of the wall 27 of a tank, the valve occupying a position as close as practicable to the tank bottom 28.

When so installed, the valve seat 2 and body or disk 6 are disposed inwardly of the wall 27 a distance sufficient to insure against 110

the water which surrounds these parts freezing, for it is a fact that the water freezes only a comparatively short distance inwardly of the wall. Consequently, when the valve 5 is first opened, any water that has accumulated in the bottom of the tank may flow out; and inasmuch as the valve and its seat are disposed well inside the freezing zone, no difficulty is encountered in opening the 10 valve.

Having thus described my invention, what I claim is:

A valve of the character set forth comprising a relatively long casing having a 15 through passageway that opens at its outer end through a side of the casing, the inner end of the casing being formed to provide a valve seat while its outer end is provided with a boss that is in substantially axial 20 alignment with the valve seat, the boss having a bore the inner portion of which is threaded while the outer portion is enlarged to provide a packing gland cavity, a compression member operating within said cav-

ity, a valve stem extending axially through 25 the casing and through the bore of said boss and having threads for cooperation with the threads of said bore, the outer end of said stem being designed for the application of an operating device, a valve body carried by 30 the inner end of the stem for cooperation with the valve seat, a shroud removably fitted over the outer end of the aforesaid boss and enclosing the protruding end of the valve stem, said shroud being reversible 35 and being designed, when in reversed position, to be applied to the outer end of the valve stem for rotating it, the shroud and casing having parts adapted to be brought into register for the application of a lock, 40 the casing incorporating means remote from its inner end for attaching it to the wall of a container so that the valve seat will be spaced a material distance inwardly of said wall, as and for the purpose specified. 45

In testimony whereof, I hereunto affix my signature.

AUSTIN L. WERTZ.
